ATTORNEY

UNITED STATES PATENT OFFICE.

FRED GUDGER, OF CARY, KENTUCKY.

NON-REFILLABLE BOTTLE.

1,300,165.

Specification of Letters Patent.

Patented Apr. 8, 1919.

Application filed September 6, 1917. Serial No. 190,067.

To all whom it may concern:

Be it known that I, FRED GUDGER, a citizen of the United States, residing at Cary, in the county of Bell and State of Kentucky, have invented certain new and useful Improvements in Non-Refillable Bottles, of which the following is a specification.

This invention relates to bottles, and particularly to that type of bottle wherein a ball valve is arranged within the neck of the bottle, and the invention aims primarily to provide a bottle of simple and improved construction which cannot readily be refilled after once being emptied of its original contents.

A further object of the invention is to provide a bottle of the character mentioned which shall be of simple and inexpensive construction, and which can be manufactured without the use of complicated mechanism.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:—

30 Fig. 1 is a longitudinal sectional view taken through a bottle constructed in accordance with the present invention, the view illustrating the bottle in upright position,

35 Fig. 2 is a similar view illustrating the bottle inverted, and

Fig. 3 is a transverse sectional view taken upon line 3—3 of Fig. 1.

Referring now to the drawings, 5 indicates the body portion of a bottle, and 6 the neck thereof. The neck portion of the bottle, adjacent its juncture with the base or body thereof, is enlarged as shown at 7, and the valve for controlling the flow of liquid to or from the bottle is arranged within this enlarged portion.

Arranged within the enlarged portion 7 of the bottle neck is a liner indicated at 8. This liner is preferably formed of hard rubber, and conforms to the shape of the com-

partment formed by the enlargement 7. The upper edge of the liner 8 is serrated as indicated at 9 while the lower edge remains smooth. A ball 10 is confined within the valve chamber and is limited in its inward and outward movement by the upper and lower edges of the liner 8. This ball is slightly larger than the diameter of the liner at its upper and lower ends, and it will be apparent that when the bottle is in upright 55 position, the ball will rest upon the lower inwardly protruding edges of the liner 7, and will effectively close the bottle neck to the entrance of fluid. When the bottle is inverted, however, the ball will rest upon 60 the serrated edge of the liner, and fluid within the bottle may flow around the ball and pass into the bottle neck through the channels formed by the serrated portion 9.

The ball 10 may be formed of any suitable material, such as glass, porcelain, or the like and is preferably constructed of a non-shrinkable and non-rustable material. In constructing the bottle, the liner 8 is forced into the open end thereof and into 75 the compartment formed by the enlargement 7. The ball is then forced into the bottle neck and beyond the serrated upper end of the liner. After the ball has been properly inserted within the compartment, the serrated end will spring back into normal position, thus preventing the ball from becoming removed from the neck.

While the above is a description of the preferred embodiment of the invention, it is 85 obvious that various changes in the minor details of construction and arrangement of parts may be resorted to without departing from the spirit of the invention as defined by the claims.

What I claim is:—

1. In a non-refillable bottle, a liner arranged within the neck of the bottle, the said liner having its upper edge serrated, and a ball arranged within the bottle neck 95 and below the said serrated edge.

2. A bottle having a neck provided with an enlarged portion, a liner arranged within the said enlarged portion, one edge of said liner being serrated, and a ball confined 100

within said enlarged portion and being adapted to move from one to the other edges of said liner.

3. A bottle having a neck provided with an enlarged portion, a liner formed of relatively thick hard rubber arranged within the said enlarged portion, the ends of said liner protruding into the neck of said bottle, one of said edges being serrated, and a ball

confined between the upper and lower edges 10 of said liner.

In testimony whereof I affix my signature in presence of two witnesses.

FRED GUDGER.
